MACHINE FOR WINDING BALLS

Boris Bogoslowsky, New York, N. Y.

Application October 6, 1939, Serial No. 298,173

2 Claims. (Cl. 242—3)

This invention relates to machines for winding balls, such as golf balls, in which an elastic strand is wound under tension to form the ball.

It is an object of the invention to provide a device by means of which the tension applied to the elastic strand may be progressively varied as the size of the ball increases during winding.

It is a further object of the invention to provide a device in which the tension applied to the elastic strand may be progressively varied until the ball has reached a predetermined size, and may thereafter be maintained at constant level.

It is a further object of the invention to provide a device of this nature which may be built into a winding machine or may be applied to existing machines as an attachment.

Other objects and advantages of the invention will appear hereinafter.

A preferred embodiment of the invention selected for purposes of illustration is shown in the accompanying drawings, in which,

Figure 1 is a front elevation of the device.

Figure 2 is a side elevation.

Figure 3 is an enlarged detail view of the adjusting device.

Referring to the drawings, the invention is illustrated in the form of an attachment for a winding machine in which the ball 1 is held and rotated by means of rollers 2 mounted in brackets 3 on shafts 4 and 4'. In accordance with usual practice the elastic strand 5 of rubber or other material to be wound is fed from a supply spool 6 around a pulley 7, and thence to the ball. The pulley 7 is secured to a smaller pulley 8 on the same shaft, and a brake band 9 rides on this pulley. Secured to the end of the brake band is a weight 10, and as will be apparent, the tension applied to the strand 5 may be increased or decreased by increasing or decreasing the weight 10, which of course increases or decreases the friction applied to the pulley by the brake band.

According to the present invention the shafts 4 and 4' are provided respectively with ball bearings 12 and 12', the inner races of which are fast to the shafts and the outer races of which are connected to the forked arms 13, 13' of the bell crank levers 14 and 14' which terminate in meshing toothed segments 15, 15'. Connected to said segments is a wire 16 which supports weight 17.

It will be understood that in winding machines where the balls being wound are supported by rollers, disks and the like, it is customary and essential that the supporting members be mounted to move apart during the winding operation

in order to accommodate the increasing diameter of the ball. Thus in the machine illustrated, the supporting rollers 2 and their shafts 4 and 4' move apart as the winding operation continues thus causing the bell cranks to swing about their pivots 18, 18'. This, in turn, will lift the weight 17.

This movement is utilized in automatically varying the tension applied to the strand as the ball increases in diameter. Thus, the weight 17 is provided with an arm 20 which engages a nut 21 on the adjusting screw 22. This screw is connected to one end of the spring 23 by a ball and socket joint 24. The other end of the spring is connected to a lever 25, fulcrumed at 26. The other end of said lever is connected to rod 27 which carries weight 10.

In using the device, before starting the winding operation, the spring 23 is disconnected from the lever 25, and the weight 10 is adjusted, by adding or removing one or more removable sections, to apply to the strand the maximum tension which is intended to be applied during the winding operation. Then, the spring 23 is again connected to lever 25, and the tension of the spring 23 is adjusted by the adjusting screw 22. It will be obvious that the greater the tension applied to the spring 23, the less will be the effective weight of the weight 10, and the less will be the tension on the strand. Consequently, the adjustment of the spring 23 should be such that the tension applied to the strand at the beginning of the winding operation will be the minimum tension desired. As winding proceeds and the weight 17 moves upwardly as previously described, the tension on the spring 23 is gradually relaxed and the effective weight of the weight 10 is gradually increased thus gradually increasing the tension on the strand.

It will be observed that if the tension on the spring 23 is entirely relieved, the full weight of the weight 10 will be applied to the strand, so that by selecting a spring 23 of the proper length, the point in the winding operation when the maximum tension will be applied to the strand may be adjusted as desired. It will also be observed that once the tension on the spring 23 is relieved, the subsequent windings will be applied at constant maximum tension.

It will be understood that the invention may be variously modified and embodied within the scope of the subjoined claims.

I claim as my invention:

1. In a ball winding machine, in combination, a pair of oppositely disposed shafts supporting

the ball being wound, said shafts being mounted for relative longitudinal movement, a weight connected to said shafts tending to move said shafts toward one another, said weight being movable as the ball increases in size, means for applying tension to the strand being wound, including a friction brake, and means operated by movements of said weight for varying the friction applied by said brake.

2. In a ball winding machine, in combination, 10 a pair of oppositely disposed shafts supporting the ball being wound, said shafts being mounted for

relative longitudinal movement, a weight connected to said shafts tending to move said shafts toward one another, said weight being movable as the ball increases in size, means for applying tension to the strand being wound, including a pulley, a brake band running over said pulley, and a weight connected to said brake band, and a yielding connection between said weights such that movement of said last named weight varies the effective weight of said first named weight.

BORIS BOGOSLOWSKY.
